TO AKTIEBOLAGET LJUNGSTRÖMS ANGTURBIN, OF STOCKHOLM, SWEDEN, A COR-
PORATION.

GOVERNING MECHANISM FOR ELASTIC-FLUID TURBINES.

1,284,845.

Specification of Letters Patent. Patented Nov. 12, 1913.

Application filed May 24, 1913. Serial No. 236,324.

To all whom it may concern:

Be it known that I, OSKAR ANTON WIBERG, a subject of the King of Sweden, residing in Finspong, Sweden, have invented new and 5 useful Improvements in Governing Mechanism for Elastic-Fluid Turbines, of which the following is a specification.

To regulate the output of a gas or steam 10 turbine a servo-motor is usually employed to actuate the main supply valve. The motor is provided with a controlling valve, which is connected to and moved by a centrifugal governor driven by the turbine. The motor is 15 also provided with what is commonly termed a follow-up device to prevent what is commonly called "hunting" and to insure stable governing. In order to take care of heavy 20 loads on the turbine it is also customary to employ an overload valve by means of which high pressure fluid can be admitted to an intermediate pressure region of the turbine, thereby shunting a portion of the high pressure blades.

25 The present invention has for its object to provide an improved arrangement of parts whereby the overload valve can be operated automatically, at the same time retaining the feature of stable governing.

30 In order to carry out my invention both the main and overload valves are provided with servo-motors for actuating them and these in turn are controlled by the same governor actuated pilot valve. Furthermore 35 the parts are so arranged that one follow-up device serves for both motors and the valves actuated thereby. The motor for the main valve is provided with loading means so proportioned that it is opened before the over- 40 load valve comes into action. The motor for the main valve is so arranged that it continues its movement after the main valve is fully opened and this makes it possible to use the same follow-up device for both main 45 and overload valves.

For a consideration of what I believe to be novel and my invention, attention is directed to the accompanying description and claims appended thereto.

50 In the drawing, Figure 1 shows my invention more or less diagrammatically as applied to a radial flow turbine of the double rotation type, and Fig. 2 is a view on an enlarged scale of the pilot valve for controlling the 55 action of the servo-motor.

1 is the main supply valve and 2 the overload valve. When only the valve 1 is open steam flows from the inlet 3 through the conduits 4 and 5 to the center of the blade system 6 and thence outwardly through the 65 blades to the point of final exhaust. When the overload valve 2 is open steam flows through the conduits 4 and 7 thereby bypassing some of the inner rows of blades.

The main valve 1 is directly connected to 66 the piston 9 which is located in a cylinder 8, the two forming the main servo-motor. The total stroke of the piston 9 may be considered as divided into two parts; the first that which is necessary to fully open the main 70 valve and the second that which is necessary to actuate the follow-up device while the overload valve is operating. The overload valve is connected to a piston 11 which is located in a cylinder 10, the two forming 75 an auxiliary servo-motor. Both motors are supplied with an actuating medium, preferably oil under pressure by the pipe or conduit 12, through which the fluid can flow to and from the motors subject to the control 80 of a pilot valve 14 which in turn is actuated by the rod 15 of a centrifugal governor (not shown). Surrounding the pilot valve and located in a casing is a ported sleeve 18 which forms a part of the follow-up device 85 and is actuated by a lever 16 which in turn is pivotally connected to the piston rod of the main motor.

Above the piston 9 of the main motor are two loading springs 17 and 18 of which the 86 spring 17 constantly loads the piston and tends to close the main valve. The spring 18 does not act until the piston has fully opened the main valve. The arrangement of the two springs 17 and 18 is of advantage 90 in that it brings about a sharply marked limit, at which the overload valve begins to open. The piston of the auxiliary motor is loaded by a spring 19, the tension of which is so proportioned that the spring on one 95 side and oil pressure on the other are balanced until the main valve 1 has fully opened.

The operation of the apparatus is as follows: When the turbine is running under 100 loads up to normal there exists in the oil pipe 12 and in the cylinders 8 and 10 a pressure which keeps the turns of the spring 17 under more or less compression and the main valve 1 is opened to an extent corre- 110

sponding to the load. If the load increases the speed of the turbine decreases somewhat and the governor rod moves the pilot valve 14 downward. This permits oil under pressure to flow through the port 20 past the annular seat 21 and through the port 22 in the sleeve 13 to the conduit 12 and cylinder 8, moving the piston 9 upward to increase the valve opening to correspond with the 10 load. The upward movement of the piston raises the right hand end of the lever 16 and since the latter is connected to the sleeve 13 the latter also moves and at the proper time shuts off further passage of oil from the port 15 20 to port 22. This action takes place each time the load increases up to what may be termed the normal. On decrease of load the parts operate in the opposite direction, oil flowing back from pipe 12 through ports 20 and 23 subject to the control of the governor rod and follow-up device. During all this action the overload valve and its motor remain inactive because the load on the 25 valve 2 and piston 11 is greater than can be overcome by the oil pressure in the pipe 12. When the main valve has fully opened and the speed of the turbine continues to fall the governor rod 15 lowers the pilot valve 14 and oil flows from the supply pipe through 30 the ports 20 and 22 to the pipe or conduit 12 and thence to the piston 11 under sufficient pressure to raise it by the desired amount against spring 19. Since the stroke of the main motor is greater than the total main 35 valve opening its piston also moves at the same time as the piston 11 but without affecting the steam admission. This has the effect at the end of a predetermined movement of the piston 9 of raising the sleeve 13 and stopping further supply of oil to the auxiliary motor and of stopping and holding the overload valve 2. This action is repeated for each change of speed due to increase of load. When the load decreases the 40 overload valve 2 is gradually closed by the auxiliary motor and thereafter when the load is normal or less the main valve assumes entire control. It will thus be seen that 45 part of the time the main valve is in control and the remainder of the time the overload valve, and that the follow-up device is in operation under all conditions with the result of stabilizing the governing under all load conditions. By the arrangement described I 50 avoid the use of any mechanical connections between the moving parts of the auxiliary motor and the follow-up device and thus bring about a simplification of the mechanism as a whole.

60 In accordance with the provisions of the patent statutes, I have described the principle of operation of my invention, together

with the apparatus which I now consider to represent the best embodiment thereof, but I desire to have it understood that the apparatus shown is only illustrative, and that the invention can be carried out by other means. 65

What I claim as new and desire to secure by Letters Patent of the United States, is:—

1. In a governing mechanism for turbines, the combination of a main supply valve means, an overload supply valve means, said means operating successively, an independent servo-motor for actuating each of the valve means, that of the main valve having a stroke greater than that required to fully open it, conduit means for supplying both motors with actuating fluid under pressure, a pilot valve for controlling the passage of fluid to both motors, and a follow-up 80 device actuated by only one of the motors for shutting off the supply of fluid pressure to both for stabilizing the governing action under all conditions.

2. In a governing mechanism for turbines, 85 the combination of a main supply valve means, an overload supply valve means, said means operating successively, an independent servo-motor for actuating each of the valve means, that of the main motor having 90 a greater stroke than is required to open its valve, means for loading the motors so that the one actuating the main valve operates before the other, a conduit which supplies fluid under pressure to both motors, a pilot 95 valve for controlling the passage of fluid through the conduit in both directions, a follow-up device coöperating with the pilot valve and actuated by the main motor only for shutting off the supply of fluid to both 100 motors under normal and overload conditions.

3. In a governing mechanism for turbines, 105 the combination of a main supply valve means, an overload supply valve means, an independent servo-motor for actuating each of said means, loading means for the overload valve which holds it closed until the main valve is fully opened, main and auxiliary loading means for the main valve which 110 exert an effective force approximately equal to that exerted by the first named loading means after the main valve is fully opened so that after the overload valve means starts into action both servo-motors will move uniformly, a pilot valve which controls both motors, and a follow-up device actuated by the main motor only.

In testimony whereof I affix my signature in presence of two witnesses.

OSKAR ANTON WIBERG.
